UNITED STATES PATENT OFFICE.

PETER A. YODER, OF WASHINGTON, DISTRICT OF COLUMBIA, AND LEWIS E. LONGLEY, OF MOSCOW, IDAHO; DEDICATED, BY MESNE ASSIGNMENTS, TO THE GOVERNMENT OF THE UNITED STATES AND TO THE PEOPLE OF THE UNITED STATES.

CANE-STRIPPING COMB.

1,322,990.

Specification of Letters Patent. Patented Nov. 25, 1919.

Application filed July 7, 1919. Serial No. 309,228.

(FILED UNDER THE ACT OF MARCH 3, 1883, 22 STAT. L., 625.)

To all whom it may concern:

Be it known that we, PETER A. YODER and LEWIS E. LONGLEY, citizens of the United States, residing in Washington, District of Columbia, and Moscow, Idaho, respectively, (whose post-office addresses are Department of Agriculture, Washington, D. C., and Moscow, Idaho, respectively,) have invented a new and useful Improvement in Cane-Stripping Combs.

This application is made under the act of March 3, 1883, chapter 143 (22 Stat. L., 625), and the invention herein described and claimed may be used by the Government of the United States or any of its officers or employees in the prosecution of work for the Government, or any person in the United States without payment to us of any royalty.

This invention relates to a comb, the object of which is to provide a simple and efficient means for stripping leaves and other waste material from cane, sorghum and other vegetable stalks.

Referring to the accompanying drawings forming a part of this specification, in which like numerals designate like parts in all the views—

Figure 1 is a front view of the entire machine, showing two combs mounted, one on each side of the rack.

Fig. 2 shows an end view of the same.

Fig. 3 shows the preferred form of comb, almost completely assembled.

Fig. 4 represents another form of the comb, completely assembled.

Fig. 5 is a perspective view of a portion of the comb.

Fig. 6 shows another form of the comb construction.

Fig. 7 is a plate fastened to the top of the rack, provided with openings permitting the insertion of the teeth of the comb and having a stripping edge.

Fig. 8 is a modified form of the plate shown in Fig. 7.

Figs. 9 to 17 show different forms of construction of the teeth of the comb.

Figs. 18 to 22 show types of blocks used to provide spacing and fastening of the teeth of the comb and to furnish an additional cane stripping edge. Fig. 18 is a sectional view through the center of the block; Fig. 19 is a sectional side view of the block; Fig. 20 is a perspective view of the block; Fig. 21 is a sectional view through the center of a special type of block shown in perspective in Fig. 22, by which the comb is fastened to the rack.

The rack 1 constitutes the frame work of the machine upon which are mounted the cane stripping combs 2. The rack consists of a top bar 3 to which the combs are fastened, which bar is supported by legs or standards 4, together with braces 5. The rack is put together in a usual and well-known manner, as with bolts or screws. The rack is also provided with a cane supporting frame 6, which is attached to the rack at any convenient point, preferably by means of flexible joints 7. This supporting frame 70 serves the purpose of preventing the cane stalks from breaking over the comb from their own weight during the stripping operation.

The comb consists of teeth 8, which are made of suitable metal, such as steel, the stripping part of which projects a suitable height above the bar 3, to which it is fastened, the height being governed by the material to be stripped—for instance, it has been found that in the stripping of Japanese cane the preferable height of the stripping plate above the bar to which the comb is secured, is 3 inches.

The stripping blade may be of any suitable shape, width, and thickness. The blade should be as thin as is compatible with the necessary rigidity. It has been found that when constructed of steel a thickness of one-sixteenth of an inch is sufficient and effective.

It is preferable to assemble the comb separately and then attach it to the top bar 3 of the rack. In assembling the comb pro-

vision must be made to hold the teeth rigidly at a suitable distance apart. One way of accomplishing this is to provide blocks of the necessary thickness to fit between the 5 blades of the teeth, as illustrated in Fig. 18. These blocks 9 may suitably be made of metal, as cast steel, shaped as further illustrated in Figs. 18, 19, and 20. The blocks are provided with transverse holes 10, to 10 admit of bolting them together with the teeth, through similar holes 11 in the teeth of the comb. To provide further stripping edge to the comb the upper end of these blocks may be shaped into a projecting edge 15 12, which edge is curved to approximate the shape of a cane stalk. To provide means for fastening the comb to the bar 3 of the rack certain of these spacing blocks 13 are of heavier construction and provided with 20 holes 14, through which bolts can be passed, fastening the assembled comb to the rack. In these blocks the stripping edge may also be provided as is done with the ordinary spacing blocks shown in Figs. 18, 19 and 20. 25 A suitable width for these blocks and consequently for the space between the teeth has been found, for the particular crop Japanese cane, generally to be about $13/16''$. If desired, some wider spaces may be built into 30 the same comb in the same manner by using wider blocks, to afford means of stripping occasional stalks of unusual thickness, as is done in Figs. 3 to 6. For crops with different size stalks a different spacing in the teeth is required and can readily be provided in a similar way.

A form of construction of the comb requiring in its construction less elaborate shop equipment is shown in Figs. 4 and 5, in 40 which the spacing blocks 15 may be of wood and the teeth 16 may be cut in a simple manner from straps of metal, like strap iron, as shown in Fig. 14. By first bending the teeth over at right angles one end 17, 45 as shown in Figs. 15 and 16, the comb may then be assembled as follows: a block 18, which may also be of wood, is nailed to a timber 19, and then a tooth set against this block, and a spacing block 15 nailed to the 50 same timber 19, and so on additional teeth and spacing blocks assembled, and finally another block of suitable size nailed against the last tooth at the other end. To further hold these teeth in place, a board 20 is nailed 55 in front of the teeth and 21 at the bottom. The completed comb thus assembled may then be bolted by suitable bolts 22 to the rack. If desired, these teeth may be cut tapering in the projecting part, as shown in 60 Fig. 17. The width of the spacing blocks 15 is governed by the thickness of the stalks

of the crop to be stripped by the comb, as in the previously described plan for the construction of the comb.

A further improvement in the last described plan of constructing the comb consists in providing an additional stripping edge for the bottoms of the spaces between the teeth of the comb, which may be done by constructing a metallic plate 23, with 65 slots 24, through which the teeth may project, this plate being fastened to the parts 70 18, 19 and 20. A further improvement in this plate is accomplished by crimping the stripping edge 25, as shown in Fig. 8. 75

Another manner of constructing the comb is by cutting the teeth out of sheet metal in a manner similar to that shown in Fig. 9, and bending them into the shape, as shown in Fig. 10, in which a stripping edge 25 is 80 again provided for the space between the teeth. These teeth may then be fastened to a bar, preferably a metallic bar, by suitable means, preferably by rivets. In a similar manner the teeth may be constructed by 85 cutting them out of sheet metal in a shape similar to that shown in Fig. 11, in bending them into a shape shown in Fig. 12, in which there is a section of metal 26, which provides additional stiffening to the strip- 90 ping edge.

In operation a number of stalks, as many as may be conveniently handled by the operator, are taken and laid on the comb in a manner so that the individual stalks may 95 drop between the teeth of the comb and then drawn, tops first, through the comb, and if necessary, this operation repeated one or more times. In actual practice with Japanese cane it has been found that from 2 to 100 3 times drawing the bunch of cane across the comb will suffice to remove the trash as nearly complete as is usually done by more tedious methods now in vogue stripping one stalk at a time. The advantage of the 105 device here described consists in handling a considerable number of stalks at one time, and thus effecting a great saving of time and labor over methods heretofore used.

From the foregoing, it is thought that the 110 construction, operation and many advantages of the herein described invention will be apparent to those skilled in the art, without further description, and it will be understood that various changes in the size, shape, 115 proportion, and minor details of construction may be resorted to without departing from the spirit or sacrificing any of the advantages of the invention.

What we claim is:

In a cane stripping machine, a frame 120 comprising standards, horizontally disposed

connecting means for the upper ends of the standards, a comb supported on either side of the said connecting means, and comprising a series of vertically disposed cutting blades, and uprights with suitable connecting means adapted to be used as a support for cane stalks, said uprights being attached to the said standards in such a way as to give stability to the cane stripping machine.

10 In testimony whereof we affix our signa-

tures in the presence of two subscribing witnesses.
